UNITED STATES PATENT OFFICE

168,448

JEWELRY DISPLAY RACK

Julius J. Hommer, Union, N. J.

Application December 26, 1951, Serial No. 17,827

Term of patent 7 years

(CL. D80—9)

To all whom it may concern:

Be it known that I, Julius J. Hommer, a citizen of the United States, residing in Union, Union County, New Jersey, have invented a new, original, and ornamental Design for a Jewelry Display Rack, of which the following is a specification, reference being had to the accompanying drawing, forming a part hereof.

Fig. 1 is a perspective view of the jewelry display rack;

Fig. 2 is a perspective view of the base; and

Fig. 3 is a front perspective view of the complete jewelry display rack, showing my new design.

I claim:

The ornamental design for a jewelry display rack, as shown.

JULIUS J. HOMMER.
